ATTORNEY

UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A SPOON.

SPECIFICATION forming part of Design No. 21,027, dated September 1, 1891.

Application filed July 11, 1891. Serial No. 399,211. Term of patent 3½ years.

To all whom it may concern:

Be it known that I, CHARLES OSBORNE, of the city, county, and State of New York, have invented a new and original Design for a Spoon, of which the following is a full, clear, and exact description, reference being had to the accompanying drawing, forming a part thereof, in which the figure shown is a front elevation of a spoon showing my design.

10 My design has relation to that class of goods known as "souvenir spoons," which are sold as souvenirs or mementos of certain localities, and this spoon is particularly intended to be sold in the United States, and to

15 this end it is designed to be emblematic of the western march of empire.

The leading feature of my design consists in the representation in the spoon-bowl of the sun setting behind distant hills and the rep-

resentation on the handle of the head of a 20 phenix. The spoon has the representation of the sun apparently setting behind distant hills produced in the bowl, and on the handle, near the head, is produced a representation of the head of a phenix surmounted by 25 a star, the Star of the West. On the shank of the handle is produced a representation of a spray of laurel, which extends downward into the top of the spoon-bowl, where it terminates in an irregular flowery mass. 30

I claim—

The design for a spoon herein shown and described.

CHARLES OSBORNE.
